UNITED STATES PATENT OFFICE.

HENRY W. O'DOWD, OF JERSEY CITY, NEW JERSEY, ASSIGNOR TO STANDARD GAS EQUIPMENT CORPORATION, A CORPORATION OF MARYLAND.

BURNER UNIT FOR GAS-HEATING APPARATUS.

Application filed October 23, 1926. Serial No. 143,556.

This invention is directed to an improved burner unit for gas stoves or ranges and for gas heating apparatus in general. In the embodiments illustrated, the improved burner unit comprises specifically an annular Bunsen burner member formed in its inner perimeter with a circular series of laterally directed flame ports, and a pan-shaped metal shell or casing surrounded by the burner member and containing a solid bed of refractory material and an overlying foraminated or reticulated wall of refractory material, said bed and overlying wall being adapted to be heated to incandescence, and forming between them a shallow combustion chamber. The flames from the burner project into the combustion chamber through a circular series of secondary air discharge openings formed in the side of the shell between the refractory bodies and adjacent or in line with the flame ports. The top of the shell, in one form of the invention, has a hood depending over the Bunsen burner so as to form a secondary air chamber common to all of the discharge openings, while, in another form of the invention the shell is fashioned so that it may be used in a gas range equipped with a burner plate which provides a similar member and secondary air chamber to contain the burner.

As the burner unit is thus constructed, the secondary air is supplied and distributed in ample quantity to all the flame jets and to all sides thereof, so that complete combustion is insured under all conditions of use, and the direct heat of the flame jets is absorbed in part by the solid refractory bed of the shallow combustion chamber and in part by the reticulated refractory top wall thereof, both of these refractory bodies being heated to a state of incandescence and radiating the heat upwardly within the area defined by the flame jets. The intense incandescence of the refractory elements in conjunction with the positive and complete aeration of the flame jets permits of combustion throughout the whole extent of the shallow combustion chamber and greatly increases the heating efficiency of the burner unit, and this whether the burner is operating at high or low pressure, it being observed that the radiant heat of the burner flames is utilized to the fullest extent. The metal shell is also useful in preventing contamination of the secondary air supply by the waste products of combustion,

as well as in guarding against back pressure, air currents, and other influences which might interfere with proper combustion or impair the heating efficiency of the burner. The improved burner unit is particularly advantageous in cases where it is desired to locate the burner unit in close proximity to the part to be heated, whether a cooking utensil or some other part, the arrangement being such that the flame jets are enveloped with secondary air and the fuel wholly consumed within the limited confines of the shallow combustion chamber. The exact construction of the parts and their advantages will best be understood from the detailed description to follow.

In the accompanying drawings:

Fig. 1 is a vertical section taken through the upper part of a range of the closed-top variety constructed in accordance with this invention;

Fig. 2 is a top plan view, on a larger scale, of part of said range and of the burner unit, parts being broken away;

Fig. 3 is a similar view of a modified form of burner, parts being broken away; and

Fig. 4 is a vertical section taken on the line 4-4 of Fig. 3.

The improved unit comprises, generally speaking, a Bunsen burner member A, and a heating radiating device including a shell or casing B, and two refractory elements C' and C² spaced apart to provide between them a shallow combustion chamber C.

The burner member A may be of any desired shape or form, depending largely upon the use to which the unit is to be put, but in the exemplary embodiments herein shown, it is annular in form and provided at its inner periphery with a single circular row or series of nibs A⁶, having orifices A⁷ through which the gaseous mixture issues and which constitute the flame ports of the burner. The fuel is supplied to the burner member, as usual, through a mixing tube A⁸, provided at its entrance end with an air chamber A⁹, into which the gas is discharged from a nozzle A¹⁰ under the control of a stop cock or valve A¹¹. In all the figures the flame ports are directed laterally, as distinguished from vertically or perpendicularly, the invention being primarily concerned with burner members formed with such laterally directed flame ports and having in view the complete aeration of the flame jets and the elimination

of heat losses incident to burners of this type. In this connection, it may be stated that ordinarily in the use of burners of the type in question, the secondary air supplied to the 5 burners reaches only the undersides of the burner flames, except possibly a trifling quantity which may percolate through the flames to the upper sides, with the result that imperfect combustion takes place, causing the 10 liberation of poisonous carbon monoxide fumes and lowering the heating efficiency of the burners. This is especially true when the burners are placed close to the cooking utensil or the part to be heated, when back 15 pressure occurs or eddies are created which limit or prevent the percolating action referred to. Moreover, in burners of this type there is considerable wastage of the heat units due to the horizontal disposition of the flame 20 jets. In other words, the direct heat of the burner is derived almost entirely from the upper sides of the flame jets, the heat given off by the under-sides and tip ends of the flames being largely dissipated instead of concentrated 25 upon the cooking utensil. With this brief explanation, it is believed the utility of the present invention will become more apparent.

The shell or casing B, which preferably is made of metal, may likewise be of any 30 desired shape or form, depending largely upon the form or shape of the burner member. In the present instance, the shell is made in the shape of a pan arranged within or surrounded by the burner. The shell is 35 formed with a circular series of secondary air openings B' in its side adjacent or in line with the flame ports of the burner. While the gas ribs A⁶ might project into or through these air openings it is preferred to have them 40 terminate short of the openings as shown.

The heat radiating elements C' and C² may similarly be of any desired shape or form, depending upon the shape of the shell in which they are located or upon the disposition 45 of the flame ports, and may be made of any desired material adapted to function in the required manner. In the present instance the element C' is in the form of a solid bed of refractory material such as fire clay, placed 50 in the bottom of the pan B to constitute the floor of the combustion chamber, while the element C² is in the form of a foraminated or reticulated plate or disk, also composed of fire clay, and supported within the pan 55 B, as by means of lugs b, to constitute the top or upper wall of the combustion chamber. The openings C³ of the element C², which may be of any desired outline, serve the dual 60 function of providing an outlet from the combustion chamber for the products of combustion and of permitting the direct passage of the heat from within the combustion chamber. Some of the heat of the flame jets will 65 be absorbed by the top wall C² and be radiated upwardly toward the part to be heated

and some will be absorbed by the bed C' and be radiated upwardly to be passed directly through the openings C³ in the top wall or be absorbed and eventually radiated upwardly by said wall. The heat absorbing and radiating surface of the combustion chamber is increased by making the same or part thereof irregular in contour, and preferably this irregularity appears in the surface of the bed C', which, as shown, see Fig. 4, is formed with numerous protuberances C⁴ of varying heights and dimensions. These protuberances C⁴ perform a further and important function in that they serve to interrupt the flow of the flames and cause them to spread in all directions, the whole interior of the combustion chamber thus becoming a mass of flames. And, when it is considered that the secondary air to support combustion is supplied to the flames on all sides, both from above as well as below, it will readily be seen that the flames as thus spread out will be thoroughly mixed with the secondary air and perfect combustion effected. The refractory walls of the combustion chamber will be heated to incandescence and all heat losses avoided by radiation from said walls, as above set forth. The construction thus described is ideal for producing an intense heat, none of which will be dissipated but all of which will be utilized to the fullest extent. Under normal conditions, combustion will be confined to or concentrated wholly within the combustion chamber C, giving the appearance of a flameless burner and producing in effect what may be termed "surface combustion".

In Figs. 3 and 4, the shell B is shown as provided with a depending hood B² which partly encloses the burner member A and forms a secondary air chamber D common to all of the discharge openings B' and open at the bottom for the admission of air thereto. The shell B is also shown as supported on the burner member A by means of recessed ribs D' depending from the inner side of the hood and interlocking with lugs A¹² rising from the burner member. As will be observed, the ribs D' and lugs A¹² are such that the shell may be readily applied to or removed from the burner by lowering or raising the shell vertically, as the case may be. Moreover, the interlocking engagement of the ribs and lugs serves to prevent turning of the shell when in place and thus maintains 110 the secondary air discharge openings B' always in proper alignment with the burner nozzles A⁶.

It will now be seen that, in the operation of the improved burner unit, secondary air 125 is supplied to the burner in pure atmospheric condition and without contamination by the waste products, being drawn up through the open bottom of the secondary air chamber D and then entrained from said chamber di-

rectly by the flame jets as they project through the openings B' into the combustion chamber C . Since the openings B' entirely surround the flame ports, each flame jet will be entirely enveloped with secondary air in order to produce complete combustion. In other words, notwithstanding the lateral disposition of the flame ports, the secondary air will reach, not merely the under sides of the flame jets, but every part thereof and in quantities regulated by the flame jets themselves. As the flame jets enter the combustion chamber, they contact with the refractory elements C' and C^2 , being spread out in all directions by the protuberances C^4 , and quickly heat the elements to incandescence. As heretofore explained, the heat absorbed by the refractory elements is radiated into the heat zone and concentrated upon the part to be heated, so that such part, whether a cooking utensil, a stove plate, or other part, will be subject substantially to the entire heat developed by the burner, the openings C^3 in the top wall C^2 permitting, as above explained, the direct passage of the heat. The refractory material, in addition to the performance of the important functions just noted, also aids in promoting combustion, serving by its incandescence to heat and consume any unburnt gases which may enter the combustion chamber from the flame ports. In fact, the flame jets, spreading in all directions as heretofore noted, will fill the combustion chamber with a mass of flames, which flames will moreover be confined to the combustion chamber, thus producing an intense heat within the limited extent of the combustion chamber without interfering with proper combustion and with the minimum consumption of fuel.

While the various elements composing the improved burner unit cooperate in a peculiar way in producing the results aimed at, nevertheless they perform individual functions which might be useful alone or in other arrangements as well. For instance, it is pointed out that, due to the restricted areas of the discharge openings B' , the pressure of the products of combustion at the flame ports is reduced to a minimum, thereby lessening the tendency to back pressure and hence more nearly preserving the initial entrainment of the primary air. Moreover, the hood B^2 protects the burner from outside disturbances and serves as a shield to prevent the clogging up of the flame ports by drippings or other foreign substances falling from above.

In the constructions herein illustrated, the metal shell B is shown as separate from the burner member and as detachably secured thereto. This arrangement is preferred for reasons of economy and for the further reason that the shell may be readily removed to permit the cleaning, repair, or replacement of the individual parts. It should be noted, however, that it would be entirely feasible

to make the shell integral with the burner member, as by casting, and this is contemplated by the present invention. It should also be noted that, insofar as the heat radiating feature is concerned the combustion chamber might be made up entirely of refractory material, in which case the shell B could be dispensed with by otherwise providing for the support of the refractory material in proper relation to the burner member.

In Fig. 1 the improved burner unit is illustrated as embodied in a gas range of the type covered in my prior Letters Patent No. 1,403,814. As shown, the range comprises an oven 2 and a closed smooth-surfaced cooking top 3, the latter being arranged above and in spaced relation to the top wall 4 of the oven and extending rearwardly beyond the back wall 5 of the range and formed throughout its length with a series of outward openings or vents 9 adapted to discharge into a flue 1 the products of combustion issuing from both the top burners and the oven burner. At this point it may be noted that the products of combustion from the oven 2 pass off through a top flue 10 communicating at the rear through openings 11 with an outlet chamber or pocket 12 having a narrow passage 13 registering with the vents 9. A burner plate 18 (preferably made of cast iron) is located in the space between the closed cooking top 3 and the oven top wall 4 and provides in effect an upper heat generating chamber 19 and a lower secondary air chamber 20. As shown, the burner plate is arranged in close parallel relation to the overlying cooking top so as to provide a shallow heat generating chamber which will serve to heat the entire top whether one or more of the burners are in operation at a time. In this connection it may be stated that it is proposed to employ a plurality of burner units below the forward portion of the cooking top, although only one is shown in Fig. 1. The burner plate 18 is recessed at the front to receive the burner unit and is designed to exclude secondary air from the heat generating chamber except that which is entrained by the burner flames. Also, the burner plate being immediately above the burner member A forms with the latter member a restricted passage or chamber 21 for the secondary air, leading to the upper sides of the flame ports B' , performing in this regard the office of the hood B^2 heretofore described. Like the hood, again, it protects the burner from outside disturbances and shields the flame ports from drippings or other foreign substances falling from above. In providing for the support of the burner unit, the burner member A is shown as the supporting element, being formed on its underside with a recessed lug A^{22} resting upon a supporting rod A^{23} in a well known manner. The shell B rests upon the burner A , being provided for this purpose with projecting ears B^5 , see

Fig. 2, which interlock with bosses A¹³ on the burner A. The upper edge or rim of the shell B abuts against the under surface of the cooking top 3, adjacent the edge of a lid opening 22 in said cooking top. As will be observed, the shell B is of substantially the same diameter as the lid opening, so that the combustion chamber C formed in the lower part of the shell is limited in effective extent to the 10 area of the lid opening; hence, when a cooking vessel is placed in the lid opening or upon the lid, the heat of the burner may be concentrated thereon, the arrangement being such that the shell with its combustion 15 chamber may be brought as close to the top as desired without danger of interfering with proper combustion. The waste products leave the shell through vents B⁴ at the top and enter the heat generating chamber 19, 20 flowing rearwardly therethrough and escaping into the flue 1. In escaping, the waste products are caused to give up their heat to the overlying rear portion of the cooking top, which may thus be said to possess a secondary calorific surface available for slow 25 cooking and warming up or keeping hot such food as may already have been cooked. The heating capacity of the escaping products is greatly increased by the shallow character of 30 the heat generating chamber, due to the close proximity of the burner plate 18 to the cooking top 3, the products being caused to pass between the two without substantial expansion in a stratum of substantially uniform 35 character which imparts practically the whole of its heat to the cooking top on the one hand and the burner plate on the other. The burner plate becoming hot, will in turn radiate its heat to the overlying cooking top and aid further in promoting the heating efficiency of the range in this respect. Moreover, some of the heat radiated from the burner plate will be imparted to the air entering the underlying secondary air chamber 40 20 and hence enable the air to be more effectively entrained at the flame ports. The effect above described will take place whether one or more of the burners are in operation at the same time, although necessarily the 45 maximum heating effect will be obtained by the use of all the burners simultaneously. Once the cooking top is heated, one burner alone will keep it hot, since the heat generating chamber is substantially co-extensive 50 with the top and allows the heated products of combustion to be distributed uniformly throughout the entire under surface of the top. The behavior of the burner unit will have been understood from the foregoing description, it being apparent that no secondary air can enter the heat generating chamber 55 except that which is entrained through the discharge openings B' by the flame jets directly.

The invention is not, of course, confined to

the precise constructions shown and described, nor to any particular construction by which the same may be carried into effect, as many changes may be made in the details thereof without departing from the main 70 principles of the invention and without sacrificing its chief advantages. It should be understood, therefore, that the invention is not limited to any specific form or embodiment, except in so far as such limitations are 75 specified in the claims.

Having thus described my invention what I claim is as follows:

1. A burner unit including, in combination, a shallow covered combustion chamber having 80 vent openings in the cover and secondary air openings at all sides, and a Bunsen burner member surrounding said chamber and having laterally directed flame ports adjacent said secondary air openings. 85

2. A burner unit including, in combination, a shallow combustion chamber comprising oppositely spaced apart walls of refractory material, one of said walls having vents for the products of combustion, and a side wall 90 extending around the combustion chamber and formed throughout its extent with secondary air openings, and a Bunsen burner member having laterally directed flame ports, one of said elements surrounding the other 95 and both arranged to permit the flames from said flame ports to enter the combustion chamber through said secondary air openings.

3. A heat radiating device presenting a horizontally disposed shallow combustion 100 chamber and comprising incandescent top and bottom walls, the former having vents for the products of combustion, and a side wall extending around the combustion chamber and formed throughout its extent with 105 secondary air openings adapted to permit the passage of flames from a gas burner into the combustion chamber.

4. A heat radiating device presenting a horizontally disposed shallow combustion 110 chamber and comprising top and bottom walls composed of refractory material, the top wall having vents for the products of combustion, and a side wall extending around the combustion chamber and formed throughout its extent with secondary air openings 115 adapted to permit the passage of flames from a gas burner into the combustion chamber.

5. A heat radiating device presenting a horizontally disposed shallow combustion 120 chamber and comprising top and bottom walls composed of refractory material, one of said walls having its inner face fashioned in irregular contour, and the top wall having vents for the products of combustion, 125 and a side wall extending around the combustion chamber and formed throughout its extent with secondary air openings adapted to permit the passage of flames from a gas burner into the combustion chamber. 130

6. A burner unit including, in combination, a heat radiating device presenting a horizontally disposed shallow combustion chamber and comprising top and bottom walls composed of refractory material, the top wall having vents for the products of combustion, and a side wall extending around the combustion chamber and formed throughout its extent with secondary air openings leading into the combustion chamber, and a Bunsen burner member having laterally directed flame ports arranged to project the flame jets through said secondary air openings into the combustion chamber.
- 15 7. A burner unit including, in combination, a horizontally disposed supporting shell, a bed of refractory material placed in the bottom of said shell, a reticulated wall of refractory material supported within the shell above the refractory bed, said shell being formed at all sides between the two refractory bodies with secondary air openings, and a Bunsen burner element having laterally directed flame ports arranged to project the flame ports through the secondary air openings into the combustion space formed between the refractory bodies.
8. A burner unit including, in combination, a ring-like Bunsen burner element formed throughout its inner perimeter with laterally directed flame ports, and a pan-shaped shell surrounded by said Bunsen burner and having secondary air openings adjacent said ports, said shell having a hood portion overhanging said burner, whereby a secondary air chamber is provided to supply air to the upper sides of the flames entering said openings.
- 30 35 9. A heat radiating device including, in combination, a pan-shaped shell, a bed of refractory material laid in the bottom of said shell, and a reticulated wall of refractory material supported in said shell above the bottom bed, said shell being formed at all sides between the two refractory bodies with secondary air openings to receive the flames from a gas burner.
10. A burner unit for gas-heating apparatus comprising an annular Bunsen burner member formed throughout its inner perimeter with laterally directed flame ports, and a combustion chamber surrounded by said burner member and having secondary air openings through which the burner flames project.
